United States Patent Office

Des. 211,265
Patented June 4, 1968

211,265

SELF-PROPELLED WINDROWER

Robert A. Skyer, Chicago, Ill., and Robert A. Calder and
Herbert W. Molzahn, Hamilton, Ontario, Canada, as
signors to International Harvester Company, Chicago,
Ill., a corporation of Delaware

Filed June 6, 1967, Ser. No. 7,375

Term of patent 14 years

(Cl. D40—1)

Fig. 1.

Fig. 2.

fig.5

fig.6

FIG. 1 is a front top perspective view of a self-propelled windrower showing our new design;

FIG. 2 is a front perspective view thereof;

FIG. 3 is a rear top perspective view showing one side thereof;

FIG. 4 is a rear top perspective view showing the other side thereof;

FIG. 5 is a front top perspective view showing a modified form of our self-propelled windrower;

FIG. 6 is a front perspective view of the form shown in FIG. 5;

FIG. 7 is a rear top perspective view showing one side of the form of FIG. 5; and,

FIG. 8 is a rear top perspective view showing the other side of the form of FIG. 5.

The dominant features of our design reside in the portions shown in full lines.

We claim:

The ornamental design for a self-propelled windrower, substantially as shown and described.
